UNITED STATES PATENT OFFICE.

ORRELL ASHTON, DECEASED, LATE OF SWAMPSCOTT, MASSACHUSETTS; BY HANNAH ASHTON, EXECUTRIX, OF SWAMPSCOTT, MASSACHUSETTS; SAID ORRELL ASHTON ASSIGNOR, BY MESNE ASSIGNMENTS, TO UNITED SHOE MACHINERY CORPORATION, OF PATERSON, NEW JERSEY, A CORPORATION OF NEW JERSEY.

TACKING MECHANISM.

1,276,000.

Specification of Letters Patent. Patented Aug. 20, 1918.

Original application filed July 11, 1912, Serial No. 708,848. Divided and this application filed February 15, 1916. Serial No. 78,518.

To all whom it may concern:

Be it known that ORRELL ASHTON, deceased, late of Swampscott, in the county of Essex and State of Massachusetts, invented 5 certain Improvements in Tacking Mechanisms, of which the following description, in connection with the accompanying drawings, is a specification, like reference characters on the drawings indicating like parts 10 in the several figures.

This invention relates to mechanism for tacking parts of a boot or shoe assembled on a last.

The present application is a division of 15 my application Serial No. 708,848, filed July 11, 1912, to which reference may be had for a complete description of an assembling machine in which the tacking mechanism of the present invention is embodied.

20 In the art of shoemaking it is frequently desirable to provide tacking devices for inserting substantially simultaneously a plurality of tacks through the upper and into the last to retain the upper temporarily in position. Such tacking devices may also be used to secure together permanently parts of the shoe materials. In such machines the shoe is usually supported mechanically 25 in a substantially fixed position which is practically the same for all sizes and styles of shoes and hence with the tacking devices fixed against movement in a direction perpendicular to the surface of the work in which the tacks are to be driven, as is the case in the prior machines, work having 30 varying inclinations of contours will not be positioned with all the tacking devices in contact therewith during the simultaneous insertion of the tacks, whereas contact of 35 all the tacking devices with the work is highly important for the best results.

An object of the present invention is to provide a machine in which all the tacking devices will engage the work irrespectively 45 of the contour or inclination of the face of the work operated upon. With this object in view a feature of the invention consists in tacking devices which are constructed and arranged for adjustment to suit the 50 various inclinations and contours of the face of the work into which the tacks are inserted. It is preferable that the adjustment of

the tacking devices be automatically effected and in the embodiment of the invention shown the mechanism comprises tacking devices which are separately movable in a direction substantially perpendicular to the face of the work into which the tacks are to be driven for automatic adaption to the 55 inclination of the contour of that face of the work when it is brought into engagement with them. As herein shown two tacking devices are provided which are connected by equalizing means so that, if, because 60 of the contour or inclination of the work, only one of the tacking devices engages the work, pressure upon that tacking device will 65 operate to force the other tacking device also into engagement with the work.

The embodiment of the invention selected 70 for illustration is a machine for securing a shoe upper to the last at the heel end of the shoe by a plurality of fastenings inserted through the rear face of the upper at different points in its height. It will be readily 75 understood that a machine provided with vertically spaced stationary tacking devices would be unsuited for this work since the sides and vertical curvatures at the rear ends of lasts are so various that an arrangement of stationary tacking devices which would fit one last would be totally unsuited 80 for another. In a machine embodying the present invention, however, the tacking devices are adjustable for all sizes and styles 85 of last, the adjustment being automatically effected by mounting the tacking devices movably in a direction perpendicular to the face of the work upon which they act and connecting them by an equalizing lever so 90 that they will adjust themselves to the curvature of the face of any shoe brought into engagement with them. Means is provided for varying the spacing between the fastenings for lasts of different heights and also 95 for supporting the work and drawing it firmly into engagement with the tacking devices and locking it in this position during their operation.

Other features of the invention including details of construction and combinations of parts will be described and defined in the appended claims.

In the drawings which illustrate the ma-

chine constituting one embodiment of the invention,

Figure 1 is a view of the machine in side elevation;

Fig. 2 is a fragmentary side view partly in section on the line 2-2 of Fig. 4;

Fig. 3 is a sectional view on the line 3-3 of Fig. 2;

Fig. 4 is a plan view of the tacking mechanism; and

Fig. 5 is a detail of the equalizing mechanism connecting the tackers.

Referring to Fig. 1 of the drawings, 10 indicates a suitable base or frame upon and 15 in which the operating parts of the machine are mounted. At the front lower portion of the frame a jack support 12 is pivoted at 14 for movement toward and from the machine. The upper portion of the supporting member 12 is hollow to permit the 20 passage therethrough of the lower end of the jack post 16. A collar 18 is formed upon the jack post and is adapted to rest upon a frame 20 to limit the downward movement 25 of the post in its support. A lever 22 is pivoted to the post 10 at a point 24 and has its forwardly projecting portion bifurcated to form two branches 26, 28. The arm 28 is arranged for engagement 30 with the lower end of the jack post 16 to elevate the same in a manner to be described.

A controlling lever 30 is pivoted at 40 between its ends to the member 12 and has a substantially fixed pivot 42 provided by a 35 link 34 connected to the frame 10. The lever carries at its lower end a roll 32 which rides upon the upper face of the arm 26 of the lever 22. The upper end 36 of the lever 30 is arranged to engage a stop 38 on the member 12 when the jack is at the limit of its outward swinging movement. It will be apparent that as the jack is swung in about the point 14 from its position in Fig. 1 the lever 30 will be swung about its pivot 42 and the roll 32 will be carried inwardly and upwardly away from the branch 26 of the lever 22 and that the lever 22 may then act in response to a weight 44 to bring the branch 28 against the lower end of the jack 50 post 16 and yieldingly raise the work against a stop 45 which limits its upward movement.

A hook 46 is pivoted to the frame 10 at a point 48 and is provided with the block 49 arranged for engagement with a stop 50 on the frame 10 to limit its downward movement. The frame 20 is pivoted to the top of the member 12 for forward and rearward adjustment by means of a screw 52 and is secured in adjusted position by a clamp bolt 54. At the rear end of the frame 20 is mounted an antifriction roll 56 and the hook 46 has formed upon it a cam surface 58 adapted for operative engagement with the roll 56. The formation of the cam surface

58 is such that as the hook descends and 65 engages the hook 56 the jack will be drawn toward the machine. The lever 46 projects rearwardly from the pivot 48 as represented at 60 in Fig. 1 and the rearward projection is connected by a rod 62 to operative parts 70 of the machine by which the hook is operated. The arrangement is such that when the machine is in its normal stopped position, as shown in Fig. 1, the connecting rod 62 is depressed and the hook 46 raised to 75 permit the jack to swing forward away from the machine. The lower end of the rod 62 carries a projection 74 arranged for engagement with the upper ends of a pair of pawls 78 which are pivoted at 80 to the 80 frame 10 and are normally pressed into engagement with a segmental ratchet 84 upon the rear end of the lever 22. When the machine is in stopped position the projection 74 engages and holds the pawl 78 out of 85 engagement with the ratchet 84 permitting the lever 22 to be moved at will. When the jack is swung into position to bring the last into proper relation to the operative parts of the machine the heel end of the shoe carried on 90 the last engages two tack blocks 88, 90.

Referring to Fig. 2, one of the tack blocks forms part of a slide 91 and the other part of a slide 92. The slides 91, 92 are mounted for movement longitudinally in suitably formed guideways 93, see Fig. 3. At the forward end of each slide a laterally projecting lug 94, Fig. 4, is arranged in co-operative relation to a spring pressed lug 96 which tends to move the slide and the tack 100 block 88 forming a part thereof forward. An equalizing lever 98, Figs. 2 and 5, is pivoted at 100 to a stationary member 101, its ends being located for engagement by the rear ends of the slides 91, 92. By this arrangement the rear end of the shoe may be firmly seated against both the blocks 88, 90 which automatically adjust themselves to the work irrespectively of the inclination or curvature of the face of the work acted 110 upon which is herein shown as the rear end of the last. If it is desired to change the relative pressure of the blocks 88, 90 upon the shoe produced by the pressure of the shoe against them, the location of the fulcrum member 101 may be changed relatively to the lever 98, for example by providing holes in the lever and in the member 101 to which the lever is pivoted. One such hole is shown at 103. If it is not desired to utilize 120 the automatic equalizing lever, movement of one or both of the slides 91, 92 may be prevented by turning a flat sided thumb nut 102 through part of a revolution to bring its rounded portion back of a shoulder 104 125 formed upon the slide 91.

A tack driving mechanism 106 is secured to each of the slides 91, 92 by a bolt 108 and

receives fastenings from any suitable form of tack supplying device 107 from which the tacks are delivered to the tack blocks through tubes 111. The driving mechanisms 5 are provided with driver levers 113 which are operated by driver cams on the main shaft of the machine in the usual manner to actuate the drivers 115. Relative adjustment 10 of the tack blocks 88, 90 in a vertical direction is provided by mounting the slides 91, 92 of the tack blocks respectively on vertically movable members 114, 116, Fig. 3, a clamping means 142 being provided to hold the members 114, 116 together after the desired 15 adjustment has been effected. The tack blocks 88, 90 are V-shaped as shown in Fig. 4 to center the shoe laterally and are slotted to permit the passage of the tacks and drivers through them into the work. Each 20 driver mechanism 106 may be adjusted about its bolt 108 by loosening the bolt and turning an adjusting screw 112 after which the bolt 108 is again tightened to hold the mechanism in adjusted position. The slots 25 in the V-blocks extend transversely and by the described adjustment the lateral position in which the tacks will be driven relatively to the face of the work presented to the blocks can be varied.

30 In the operation of the machine the shoe upon the jack is placed on the last pin of the jack post 16 and is moved toward the machine, the jack post 16 being yieldingly raised during this movement as described.

35 When the shoe has been positioned against the stop 45 and against the tack blocks 88, 90 the treadle 70 is depressed to start the machine, whereupon the connecting rod 62 is operated and the hook 46 swings about 40 its pivot 48. The cam 58 coöperates with the cam roll 56 to draw the work firmly against the tack blocks which automatically adapt themselves to the contour of the heel end of the last by reason of the equalizing 45 lever 98. If the pressure of one of the tack blocks relatively to the other is too great the position of the fulcrum pin 100 may be changed. As the rod 62 which is connected to the rear end of the hook 46 rises the 50 projection 74 releases the pawls 78 one of which will then engage a tooth of the ratchet 84 and lock the jack against depression; tacks are then dropped by the tack supplying device into the upper ends of 55 the tube 111 and fall through the tubes, being carried by their own momentum into position in front of the horizontal or upwardly inclined drivers 115. The drivers then operate to insert the tacks through the 60 tack blocks 88, 90. The jack is then released and the machine comes to rest.

Having fully described my invention, what I claim as new and desire to secure by United States Letters Patent is:—

1. In a machine of the class described, the 65 combination of a plurality of tacking devices arranged to contact with the work and mounted for movement in directions perpendicular to the face of the work which they engage and into which the tacks are to 70 be driven, and means for permitting relative movement of either of the devices by pressure of the work upon the other device until both devices come into bearing upon the work, and then supporting both devices 75 rigidly against pressure of the work.

2. In a machine of the class described, the combination of a plurality of tacking devices adapted to contact with the work and mounted for movement perpendicular 80 to the face of the work with which they contact and into which the tacks are to be inserted, and means for automatically effecting, by movement of one of the tacking devices adjustment of another tacking device 85 so that each will contact with the work.

3. In a machine of the class described, the combination of a plurality of tacking devices adapted to engage a face of the work and mounted for relative movement perpendicular 90 to said face of the work, said devices being constructed and arranged to insert tacks into the said face of the work, and equalizing means between the tacking devices for causing movement of one of the 95 devices by movement of another.

4. In a machine of the class described, the combination of a pair of tacking devices mounted for movement substantially perpendicular 100 toward and from the face of the work into which the tacks are to be driven, and means connecting the tacking devices for effecting equal and opposite movements of the tacking devices when the work is pressed against one of them. 105

5. In a machine of the class described, the combination of a pair of tacking devices mounted for movement perpendicular to the face of the work into which the tacks are driven and adapted to be moved by pressure of the work against them, and means 110 for distributing the pressure between the tacking devices in a predetermined ratio.

6. In a machine of the class described, the combination of a work support, a plurality of tacking devices spaced apart and arranged to be engaged by the face of the work into which the tacks are driven, equalizing connections for adjusting the tacking devices to the engaged surface of the work 115 irrespectively of its contour, and means for moving and holding the work support to effect a firm engagement between the work and the tacking devices. 120

7. In a machine of the class described, the 125 combination of a work support, a plurality of tacking devices spaced apart and arranged to be engaged by the surface of the

- work into which the tacks are driven, equalizing connections for adjusting the tacking devices to the engaged surface of the work irrespectively of its contour, and
- 5 means for moving and holding the work support to effect a firm engagement between the work and tacking devices.
8. In a machine of the class described, the combination of a work support, a plurality of tacking devices spaced apart and arranged to be engaged by the surface of the work into which the tacks are driven when the work is moved toward the devices in the direction in which the tacks are inserted,
- 10 equalizing connections for adjusting the tacking devices to the surface of the work engaged thereby irrespectively of its contour, means for automatically moving the work support toward the tacking devices
- 15 and holding it there during the operation of the tacking devices.
9. In a machine of the class described, the combination of a plurality of tacking devices disposed one above the other, an equalizing mechanism connecting the devices and arranged to permit relative movement
- 20
- 25

of the devices to enable them all to contact with the face of a shoe into which the tacks are to be driven.

10. In a machine of the class described, the combination of a pair of tacking devices having their shoe engaging faces shaped to center relatively thereto the rear face of the counter of a shoe presented to them, said devices being constructed for relative movement by the pressure of the shoe and arranged to distribute the pressure between them.

11. In a machine of the class described, the combination of a slotted V-block for centering the rear end of a shoe, a tacking mechanism located to insert tacks through the V-block, and means for effecting lateral adjustment of the tacking mechanism relatively to the block to vary the location of the tack relatively to the rear end of the shoe.

In testimony whereof I have signed my name to this specification.

HANNAH ASHTON,
Executrix of the will of Orrell Ashton, deceased.
